To all whom it may concern:

Be it known that I, Walter D. Teague, a citizen
of the United States, residing at Forest Hills, in
the county of Queens, State of New York, have
invented a new, original, and ornamental Design
for a Clock Case, of which the following is a
specification, reference being had to the accom-
panying drawing, forming a part thereof.

The figure is a front perspective view of a clock
case showing my new design.

I claim:

The ornamental design for a clock case as
shown.

WALTER D. TEAGUE.
